UNITED STATES PATENT OFFICE.

FREDERICK HERR, OF NEW YORK, N. Y.

HAT-BRIM PRESS.

1,093,411.

Specification of Letters Patent. Patented Apr. 14, 1914.

Application filed June 13, 1913. Serial No. 773,425.

To all whom it may concern:

Be it known that I, FREDERICK HERR, a citizen of the United States, and a resident of the city of New York, Astoria, borough 5 of Queens, in the county of Queens and State of New York, have invented a new and Improved Hat-Brim Press, of which the following is a full, clear, and exact description.

10 Among the principal objects which the present invention has in view are: to provide a press of the character mentioned with means for stretching the brim while in the press and under control; to provide power 15 means manually operable for exerting an extra pressure upon the material forming the brim, said means being controllable to conform to the inherent conditions of various materials; and to simplify the mechanism by which the operation is performed.

20 One embodiment of the present invention is shown in the accompanying drawings, in which—

25 Figure 1 is an elevation of a press having mounted thereon an auxiliary plunger constructed and arranged in accordance with the present invention, a shape being shown in section and as mounted on the bed table; Fig. 2 is a detail view showing in vertical 30 section a shape, an auxiliary plunger and mounting therefor, constructed and arranged in accordance with the present invention; Fig. 3 is a vertical section of a modified form of the auxiliary plunger and a shape 35 to be used in conjunction therewith.

As seen in the drawings, the cross head 8 of the conventional press is provided with a boss 9 centrally located to receive a screw-threaded shaft 10. The shaft 10 is provided 40 with a hand wheel 11 at the upper end thereof, and is rotatively mounted in a socket 12. The socket 12 is raised on a bolting plate 13, to which is suitably secured a palette or plunger plate 14. The bolting plate 13 has 45 one or more bosses 15 on which is rigidly mounted a guide rod or rods 16. These rods serve to hold in line the plate 14 with the recess 17 of a shape 18. The shape 18 is of conventional construction, having resting 50 legs 19 for supporting the shape on a table 20.

The cross head 8 has depended therefrom a clamping ring 21 of conventional shape and mounting, which ring 21 is arranged to 55 strike upon an annular offset 22 with which the shape 18 is provided, to clamp rigidly

the material A from which the hat brim is being constructed. As in the conventional presses, the cross head 8 and parts connected therewith are drawn down into operating 60 relation upon the shape 18 by means of a foot power treadle 23.

When the cross head 8 and ring 21 connected therewith are moved down to clamp the material A, to hold the edge thereof on 65 the offset 22, the palette 14 rests lightly above the material where the same extends across the recess 17. The interior of the recess 17 and the periphery of the palette 14 are formed to the shape of the head of the 70 wearer. By now rotating the shaft 10 by means of the hand wheel 11, the palette is forced down upon the material A until rigidly clamped between the periphery of the palette 14 and the side of the shape 18. 75 In this position, the brim is permitted to dry.

It will be noted that the above-described movement of the palette 14 has been accomplished by stretching the material A forming 80 the hat brim. In this position, the material is permitted to dry, the brim thereafter retaining its shape as imparted by the press.

It is obvious that the auxiliary press having 85 the palette 14, shaft 10 and hand wheel 11, permits an extra amount of pressure to be applied to the material from which the brim is being constructed, unaccompanied by the danger which would otherwise be 90 present if the pressure was exerted by the machine uncontrolled by the hand of the operator.

In Fig. 3 of the drawings, a modified form 95 of shape and palette are shown. In this figure, the shape 24 is provided with a central opening or passage 25, and with an annular groove 26. A palette 27 is also provided with an anvil head 28 and an eyeleted pendant shank 29. When using the modified 100 form of shape and palette, the material A is preliminarily stretched over the shape and bound thereon by a wire 30. The material A is perforated to provide a passage for the shank 29, which is then placed in position 105 on the shape, to rest upon the material A above the passage 25. A maul is now employed for striking upon the anvil head 28 to drive the palette 27 to its seat at the upper end of the passage 25. This extends the 110 shank 29 below the lower face of the shape 24 to permit the insertion of the tapered

pin 31 through the eyelet formed in the lower end of the shank 29. The pin 31 having been inserted through said eyelet, to bridge the passage 25, serves thereafter as 5 a power-augmenting element to increase the pressure or pull of the palette 27 to draw the material more tightly over the shape 24. This is accomplished by driving the tapered pin 25 through the eyelet in the shank 29.

10 Claim.

15 A press as characterized, comprising a table; a cross-head; a clamping ring mounted on said cross-head; means for raising and lowering said cross-head and clamping ring; a hat-brim shape adapted to rest on said table and embodying an annular offset and a central depression, said offset registering with, and forming a seat for, said

clamping ring; a relatively thin plunger plate adapted to fit within said depression 20 to shape an inner edge of a hat-brim and to mark the same for guidance in cutting away the center of the material of which the hat-brim is composed; and a manually manipulated auxiliary press for said plunger plate 25 to force the same into said central depression after the cross-head and clamping ring have been placed in service relation.

In testimony whereof I have signed my name to this specification in the presence of 30 two subscribing witnesses.

FREDERICK HERR.
